INVENTOR
S. H. Ransom

UNITED STATES PATENT OFFICE.

SAMUEL H. RANSOM, OF ALBANY, NEW YORK.

DESIGN FOR THE PLATES OF A PARLOR OR HEATING STOVE.

Specification forming part of Design No. 6,732, dated June 24, 1873; application filed April 18, 1873.

To all whom it may concern:

Be it known that I, S. H. RANSOM, of the city of Albany, and county of Albany, and State of New York, have invented a Design for the Plates of a Parlor or Heating Stove, of which the following is a specification:

The nature of my design is fully represented in the accompanying engraving, to which reference is made.

A represents the top of the stove, ornamented on its surface with series of alternate leaf-work and bead-work, as shown. B represents the door and frame, ornamented on its face with rosette in center and a series of beads, and around its outer surface, as follows: On the top with fan-shaped center and scrolls; on the sides with spear-top shaped ornamentation. C represents the damper, the "valve" being, at its lower portion, a combination of "bead" and "ray" work; its upper portion being scrolls, which form the arm of the valve. The base of the body of the damper is a series

of scroll and ray work, finished at the upper edge by a row of leaf-work.

I do not claim the peculiar formation or shape of this damper.

D represents the base, with "ogee" molding, finished with alternate ornaments of leaves with scroll base and graduated flutings, with scroll base interspersed with small raised half-spheres. E represents the leg, ornamented with graduated flutings dropping from the scroll-work.

I do not claim the general formation of moldings, except as mentioned in D.

What I claim as my invention is—

A design for the plates of a parlor or heating stove, substantially in the manner above mentioned.

S. H. RANSOM.
